UNITED STATES PATENT OFFICE.

FREDERICK F. CLARKE, OF FRANKLIN, PENNSYLVANIA, ASSIGNOR TO COLBURN MACHINE TOOL COMPANY, OF FRANKLIN, PENNSYLVANIA, A CORPORATION OF PENNSYLVANIA.

SPRING-COUNTERBALANCE FOR THE RAMS OF BORING-MILLS.

1,185,060.

Specification of Letters Patent. Patented May 30, 1916.

Application filed February 10, 1914. Serial No. 817,807.

To all whom it may concern:

Be it known that I, FREDERICK F. CLARKE, citizen of the United States, residing at Franklin, in the county of Venango and 5 State of Pennsylvania, have invented certain new and useful Improvements in Spring-Counterbalances for the Rams of Boring-Mills, of which the following is a specification.

10 This invention relates to improvements in boring mills, and more especially to an improved counterbalance for the ram of a boring mill.

15 The particular object, construction, and application and utility of my invention are herein set forth with sufficient clearness to enable those skilled in the art to which it appertains, to make and use the same.

The object of this invention is to provide 20 a spring counterbalance for the ram of a boring mill, which will not only counterbalance said ram, thus rendering the same easy of vertical or longitudinal adjustment and manipulation, but will also dispense 25 with the cumbersome, inconvenient and expensive counterweights heretofore employed for such purpose, together with the connections, supports, pulleys and cables or chains which their employment necessitates.

30 The construction and application of my improved spring counterbalance are clearly shown in the drawings which form a part hereof, and in which:

Figure 1 is a front elevation of one end of 35 the cross-rail of a boring mill, showing a head mounted thereon, which head comprises a saddle, a swivel and a ram or tool-bar which is mounted in said swivel, to which ram or tool-bar is applied my improved 40 spring counterbalance. Fig. 2 is a section on line II—II of Fig. 1. Fig. 3 is an enlarged section upon substantially the same line upon which Fig. 2 is taken, and in this view my counterbalance and its coöperating 45 elements only, are shown in full lines for the purpose of more distinctly and concisely pointing out my invention. Fig. 4 is a sectional view, upon substantially the same line II—II of Fig 1, showing a head which does 50 not employ the swivel element, the ram being mounted directly in the saddle, since my improved counterbalance is equally applicable to either form of head.

The construction of my improved coun-

terbalance, as illustrated in said drawings, 55 is substantially as follows:

The ram or tool-bar 1 of a boring mill may be mounted either in the swivel 2 of the head, as clearly shown in Figs. 1, 2 and 3, or mounted directly in the saddle as shown in 60 Fig 4. The vertical feed or adjustment of said ram 1 is accomplished by means of certain gearing, which comprises a rack 3, secured to or formed upon one side of said ram and a pinion 4 which meshes with said 65 rack. Said pinion 4 is mounted upon and keyed to a shaft 5 that passes revolvably through said swivel 2 or the saddle 10, and keyed to the rear end of said shaft is a worm-wheel 6 which is arranged to be revolved by 70 the worm 7. Said worm 7 is slidingly but non-revolvably mounted upon the shaft 8, and is caused to slide upon or move longitudinally of said shaft by means of the brackets 9—9, which are secured to the said saddle 75 10 of the boring mill. Shaft 8 is usually adapted and arranged to be both power and manually revolved, and for the purpose of such manual actuation, the outer end 11 of said shaft 8 is adapted for the application 80 of a crank 11^c, which is preferably the automatically-releasing crank shown and described in my application for Letters Patent of the United States, filed June 25, 1913, Serial No. 775,757. By means of this gear- 85 ing and its equipment thus far described, the ram 1 may be fed to its work, raised, lowered, and adjusted vertically, but because of the weight of said ram, it is desirable and necessary for ease and convenience, and accuracy 90 of operation, to counterbalance the same, and this has heretofore usually been accomplished by means of a counterweight, which is more or less cumbersome, occupies considerable 95 room and in some cases requires a special preparation of the foundation for the machine, in respect to providing room below the floor-line for the reception of said weight. In the place of such counterweight, I substitute a spiral spring 12 for which I provide a case or barrel 13, which is revolvably-mounted within the swivel 2 or the saddle 10. The outer end of said spring is secured to the wall of said barrel 13 by means of the pin 14, and the inner end of said spring is secured 100 to shaft 15 which passes through the spring, which shaft is provided at either end with bearings within said swivel or saddle, as the 105

case may be. Formed integrally with said barrel 13 is a sleeve 16, through which shaft 15 passes revolubly, and upon which sleeve is mounted and keyed a pinion 17. It will thus be noted that said barrel is revoluble upon said shaft 15 and that pinion 17 is revoluble with and rigidly affixed to said barrel. Meshing with said pinion 17 is an intermediate pinion 18, which, in turn, meshes 10 with said pinion 4, which, as previously stated, is keyed to the shaft 5 and meshes with the rack 3. To the outer end of shaft 15 is keyed a ratchet-wheel 19, for which an engaging-pawl 20 (see Fig. 1), is provided. 15 Formed integrally with said ratchet-wheel 19 is a hexagonal sleeve 21, to which a key,—or other suitable device, such as a wrench, or crank,—may be applied for the purpose of revolving said wheel and the thereto-keyed shaft 15 whereby the desired 20 counterbalancing-tension or recoiling-force of spring 12 is produced. When such proper tension has been secured, shaft 15 and ratchet 19 are retained in the stationary position by means of said pawl 20, and as ram 1 is moved vertically, barrel 13 is caused to revolve and thus to wind up and unwind 25 said spring 12.

From the above explanation, it will readily

be understood that the weight of the ram 1 30 is counterbalanced by the recoil-force or potential energy of the spring 12, and thus a vertical movement of said ram may be easily accomplished through the actuation—manual or otherwise—of shaft 8, and not only 35 this, but in addition thereto, working-adjustments of said ram are much more easily and certainly maintained when the ram is thus balanced.

I claim:

In a boring mill, in combination, a saddle, a swivel mounted upon said saddle, a ram mounted in said swivel and movable vertically or longitudinally therein and provided with a rack, a pinion arranged in mesh with 45 said rack operable to cause said vertical or longitudinal movement of said ram, a spiral spring also mounted in said swivel, a spring-pinion to which said spring is operably connected, and means operably connecting said 50 spring-pinion to said rack-engaging pinion, for the purpose set forth.

In testimony whereof I affix my signature in presence of two witnesses.

FREDERICK F. CLARKE.
